UNITED STATES PATENT OFFICE.

GEORGE K. THOMPSON, OF MAPLEWOOD, NEW JERSEY, ASSIGNOR TO AMERICAN TELEPHONE AND TELEGRAPH COMPANY, A CORPORATION OF NEW YORK.

DESIGN FOR A HAND TELEPHONE.

Application filed December 31, 1923. Serial No. 8,197. Term of patent 14 years.

To all whom it may concern:

Be it known that I, GEORGE K. THOMPSON, a citizen of the United States, residing at Maplewood, in the county of Essex and State of New Jersey, have invented a new, original, and ornamental Design for Hand Telephones, of which the following is a specification, reference being had to the accompanying drawing, forming a part thereof.

The drawing is a perspective view of a hand telephone, showing my new design.

I claim:

The ornamental design for a hand telephone, as shown.

In testimony whereof, I have signed my name to this specification this 27th day of December, 1923.

GEORGE K. THOMPSON.
